UNITED STATES PATENT OFFICE.

JOHN H. DERBY AND ERNEST S. CLAYTON, OF NEW YORK, N. Y., ASSIGNEES TO
AMERICAN FIRE PREVENTION BUREAU, INC., A CORPORATION OF NEW YORK.

ELECTRIC-CIRCUIT THERMOSTAT.

1,347,735.

Specification of Letters Patent. Patented July 27, 1920.

Application filed December 5, 1917. Serial No. 205,524.

To all whom it may concern:

Be it known that we, JOHN H. DERBY and ERNEST S. CLAYTON, citizens of the United States, residing at New York city, N. Y., have invented certain new and useful Improvements in Electric-Circuit Thermostats, of which the following is a clear, full, and exact description.

This invention relates to an electric circuit thermostat, and particularly of the type operated by the influence of any unusual temperature, such as might be due to a fire, to close an electric circuit and give a fire alarm signal.

One object of the present invention is to provide an easily and cheaply manufactured product of few parts and of simple construction, which can be rolled together into lengths of any desired extent for installation in a building or other area which it is desired to protect against fire.

A further object is to safely insulate the parts of the circuit from one another under all conditions except the presence of heat, and to protect the short circuiting means for said circuit against the intrusion of moisture, dirt, or other foreign material, whereby said thermostat may be left in exposed condition for long periods of time without deterioration, and yet be ready for instant service when called upon for operation.

A further object of the invention is to provide a visible signal at various points along the line of the thermostat so as to indicate where the same has operated.

Various other objects and advantages of the invention will become apparent from the following description when taken in connection with the accompanying drawings, which describe and show the preferred embodiment of the invention, and in which—

Figure 1 is a plan view from the underside of a length of the complete thermostat; Fig. 2 is a cross-section of the same along line 2-2 of Fig. 1;

Fig. 3 is a group view of the several parts of the thermostat detached and in perspective; and

Fig. 4 is a sectional view of a modification.

Referring more particularly to the drawings, 1 indicates a base strip of some electrical conducting material fusible at a comparatively high temperature, preferably phosphor bronze, so as to serve as a good

conductor for an electric circuit, and rolled in channeled form to provide a thin flat bottom wall and abruptly upturned side walls 2 with laterally extending flanges 3. As shown in Fig. 1, the bottom wall of said channel 1 is formed at intervals there along with transverse corrugations 4 and miniature openings 5 therethrough, the purpose of which will be later described.

7 indicates a strip of easily fusible solder 65 that is fusible at a comparatively low temperature, and which is adapted to melt in the presence of any unusual degree of heat, such as might be produced by a fire in the vicinity thereof. As shown, the strip of 70 solder 7 is co-extensive with the channel member 1 and in close contact with the bottom wall thereof, with its edges confined between the side walls 2. The solder strip is also preferably formed with transverse 75 corrugations at intervals interfitting with those of the channel strip 1.

Above the strip of solder 7 is laid a thin flat strip of conducting material fusible at a comparatively high temperature, such as 80 phosphor bronze, to serve as a second conductor, indicated at 8, and completely surrounded by a sleeve of flexible insulating material such as varnished silk, indicated at 9. At intervals along the length of the insulating sleeve 9 are series of perforations, such as 10, through which the fusible solder 5 is adapted to spread when melted, to form an electrical connection between the channel conducting member 1 and the strip 8. 85 An additional cover strip 10^a is provided above the insulated conducting strip 8 as shown, and said cover strip 10^a likewise has lateral flanges 11, which are interlocked in any suitable manner with the flanges 3 90 of the base member 1, to firmly clamp the parts together and form a closed continuous length casing for the insulated conductor 8 and the short circuiting solder strip 7. The interlocked flanges 3 and 11 are provided with bolt holes 6 preferably in staggered relation, whereby said casing may be attached to a support such as a ceiling or wall of a room.

It will be noted also that the cover strip 105 10^a is preferably arched downwardly at its central portion to firmly press the parts within the casing against the bottom wall of the channel member 1, to thereby facilitate the spreading of the solder through the per- 110

forations of the silk sleeve when melted. The corrugations 4, upon the channel member 1, interfitting with similar corrugations of the solder strip 7, tend to prevent the spreading of the solder lengthwise of said channel member when melted, and the confining side walls 2 prevent the lateral spreading of the solder, thus forcing the solder, when melted, to spread upwardly 10 through the perforations of the silk sleeve 9 into bridging contact with the second conductor 8. The corrugations 4 are preferably impressed on said member 1, and the solder strip simultaneously by passing the same together through corrugating rolls, previous to the complete assembling of the parts. The miniature holes 5 furnish openings through which a small portion of the solder will bulge, when melted, to indicate which 20 part of the thermostat has operated.

The channel member 1 may be connected to one wire 12 of an electric circuit and the conductor 8 to the other wire 13 of said circuit, and it will be obvious that upon the 25 melting of any portion of the solder 7, the conductors 1 and 8 are short circuited so that any suitable electric signal may be given at a distant station. It will also be observed that the thermostat can be manufactured by 30 the simple process of rolling several flat strips together into any length desired, and that it may be strung about a building with even less cost than ordinary electric wiring, as it provides its own attaching means and 35 its own insulation.

In the modification shown in Fig. 4, the conducting strip 8 is dispensed with and the cover 10^a is employed as one element of the conducting circuit, and the channel member 40 1, as before, is employed as the other conducting member of the circuit. The insulating sheet of varnished silk 9 is laid above the solder strip 7 and its side portions 9' are extended laterally and co-exten- 45 sively with the side portions 11 of the cover strip 10^a and are turned together with the flanges 11 of the cover strip around the edges of the channel strip 1, the varnished silk sheet 9 thus completely insulating the 50 cover strip 10^a from the channel strip 1. In order to secure this modified form of device to a support, additional clips such as 20 are preferably employed, having ordinary screws 21 for fastening the same and 55 adapted to engage the flanges of the thermostatic device, as shown, to support the same in position.

While we have shown and described what is considered to be the preferred embodiment of my invention, it is to be understood that the invention is not to be limited to this arrangement but may be embodied in other forms and arrangement of parts, without departing from the scope of the invention as claimed.

What we claim as new is—

1. In an electric circuit thermostat, comprising a continuous length casing, said casing including within its area side walls and separated conductors for an electric circuit 70 normally insulated from one another by a strip of insulating material having perforations therethrough, a thin flat strip of easily fusible conducting material confined between said side walls and adapted, when fused, to spread through said perforations, and electrically bridge said circuit conductors, said strip of said insulating material and strip of easily fusible conducting material being coextensive with said casing. 30

2. An electric circuit thermostat of continuous length having a thin flat bottom wall forming a conductor and abruptly upturned side walls, a second conductor normally insulated from said bottom wall by a continuous strip of insulating material having perforations therethrough, a thin flat strip of easily fusible conducting material co-extensive with said bottom wall and with its lateral edges confined between said side 90 walls and adapted, when fused, to spread through said perforations and electrically bridge said circuit conductors. 85

3. An electric circuit thermostat of continuous length having a thin flat bottom wall 95 forming a conductor and abruptly upturned side walls, a second conductor normally insulated from said bottom wall by a continuous strip of insulating material having perforations therethrough at intervals there- 100 along, a thin flat strip of easily fusible conducting material co-extensive with said bottom wall and confined between said side walls and adapted, when fused, to spread through said perforations and electrically 105 bridge said circuit conductors.

4. An electric circuit thermostat of continuous length having a thin flat bottom wall forming a conductor and abruptly upturned side walls, a second conductor normally insulated from said bottom wall by a continuous strip of insulating material having perforations therethrough, a thin flat strip of easily fusible conducting material co-extensive with said bottom wall and with its lateral edges confined between said side walls and adapted, when fused, to spread through 110 said perforations and electrically bridge said circuit conductors, said bottom wall having raised surfaces transversely thereof and at 115 intervals along its length to retard the lengthwise spreading of said fusible material when melted. 120

5. An electric circuit thermostat of continuous length having a thin flat bottom wall 125 forming a conductor and abruptly upturned side walls, a second conductor normally insulated from said bottom wall by a continuous strip of insulating material having perforations therethrough, a thin flat strip 130

of easily fusible conducting material co-extensive with said bottom wall and with its lateral edges confined between said side walls and adapted, when fused, to spread through 5 said perforations and electrically bridge said circuit conductors, said bottom wall and co-extensive fusible strip having interfitting corrugations transversely thereof at intervals therealong to retard the lengthwise 10 spreading of said fusible material when melted.

6. An electric circuit thermostat, comprising a channeled strip having an electrically conducting portion and a cover strip fastened together to form a continuous length 15 casing, a second conductor normally insulated from the electrically conducting portion of said channeled strip by a continuous strip of insulating material having perforations therethrough, a thin flat strip of easily 20 fusible conducting material co-extensive with said channeled strip, and confined within said channeled portion and adapted, when fused, to spread through said perforations and electrically bridge said circuit 25 conductors.

7. An electric circuit thermostat, comprising a channeled strip having an electrically conducting portion and a cover strip with 30 interlocking lateral flanges forming a continuous length casing, a second conductor normally insulated from the electrically conducting portion of said channeled strip by a continuous strip of insulating material 35 having perforations therethrough, a thin flat strip of easily fusible conducting material co-extensive with said channeled strip, and confined within said channeled portion and adapted, when fused, to spread 40 through said perforations and electrically bridge said circuit conductors.

8. An electric circuit thermostat, comprising a continuous length casing having a thin flat bottom wall and abruptly upturned 45 side walls of comparatively high temperature fusing material and serving as a conductor for an electric circuit, a thin flat strip of comparatively low temperature fusing conducting material lying lengthwise of said bottom wall in contact therewith and with its lateral edges confined between said side walls, a second thin flat strip of comparatively high temperature fusing conducting material surrounded by a 50 sleeve of insulating material and lying above said low fusible strip, said insulating sleeve having perforations therethrough on the side facing said low temperature fusing strip, said low temperature fusing material 55 adapted, when melted, to spread through said perforations and electrically bridge said high temperature fusing conductors.

9. An electric circuit thermostat, comprising a channeled strip and a cover strip with 60 interlocked lateral edges forming a con-

tinuous length casing, one of said strips serving as a conductor for an electric circuit, a thin flat strip of easily fusible conducting material coextensive with said channeled strip, and lying within said 70 channel and in electrical contact with said conducting strip, a thin flat metallic strip also coextensive with said channeled strip and serving as a second conductor and entirely surrounded by a sleeve of continuous, 75

flexible, insulating fabric lying contiguous to said easily fusible strip, said insulating sleeve having perforations therethrough on the side adjacent said easily fusible strip, said fusible material adapted, when melted, 80 to spread through said perforations and electrically bridge said circuit conductors.

10. An electric circuit thermostat, comprising a channeled strip and a cover strip with interlocked lateral edges forming a 85 continuous length casing, said lateral flanges having bolt holes therethrough at intervals to provide attaching means for said casing, one of said strips serving as a conductor for an electric circuit, a thin flat strip of easily 90 fusible conducting material coextensive with said channeled strip, and lying within said channel and in electrical contact with said conducting strip, a thin flat metallic strip serving as a second conductor and entirely surrounded by a sleeve of continuous, 95 flexible, insulating fabric lying contiguous to said easily fusible strip, said insulating sleeve having perforations therethrough on the side adjacent said easily fusible strip, 100 said fusible material adapted, when melted, to spread through said perforations and electrically bridge said circuit conductors.

11. An electric circuit thermostat, comprising a channeled strip and a cover strip forming a continuous length casing, one of 105 said strips serving as a conductor for an electric circuit, a thin flat strip of easily fusible conducting material coextensive with said channeled strip and lying within said channel and in electrical contact with said conducting strip, a thin flat metallic strip also coextensive with said channeled strip and serving as a second conductor and entirely surrounded by a sleeve of continuous, 110 flexible, insulating fabric lying contiguous to said easily fusible strip, said insulating sleeve having perforations therethrough on the side adjacent said easily fusible strip, said fusible material adapted, when melted, 115 to spread through said perforations and electrically bridge said circuit conductors, said channeled strip having raised surfaces transversely thereof and at intervals along its length to retard the lengthwise spreading of said fusible material when melted. 120

Signed at New York city, N. Y., this 30th day of November, 1917.
